US00D959638S

(12) **United States Design Patent** (10) Patent No.: **US D959,638 S**
Ahn (45) Date of Patent: ** Aug. 2, 2022

(54) **PORTABLE FAN**

(71) Applicant: **SPIGEN KOREA CO., LTD.**, Seoul (KR)

(72) Inventor: **Deok Hyun Ahn**, Seoul (KR)

(73) Assignee: **SPIGEN KOREA CO., LTD.**

(**) Term: **15 Years**

(21) Appl. No.: **29/684,731**

(22) Filed: **Mar. 22, 2019**

(51) LOC (13) Cl. **23-04**

(52) U.S. Cl.

USPC **D23/382**

(58) **Field of Classification Search**

USPC D23/382
CPC F04D 25/0673; F04D 25/08; F04D 25/084;

(57) **CLAIM**

The ornamental design for a portable fan, as shown and described.

DESCRIPTION

FIG. 1 is a front perspective view of a portable fan showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another front perspective view thereof.

The broken lines depict portions of the portable fan that form no part of the claimed design.

1 Claim, 9 Drawing Sheets
